Property Custodian

Application January 18, 1941, Serial No. 374,960
In the Netherlands March 21, 1940

7 Claims. (CL 179—171)

In the copending application, Ser. No. 333,088, filed May 3, 1940, there is described a high-frequency amplifier circuit comprising at least one amplifier valve whose cathode is provided with at least two leads, one of which, for the oscillations to be amplified, is included in the input circuit and another in the output circuit, and in which capacities are connected between the control grid and the point of the cathode which is connected to the cathode lead included in the input circuit and between the control grid and that end of the cathode lead included in the output circuit which is not connected to the cathode, and one or both cathode leads comprises or comprise impedances of which at least one has an inductive character, said capacities and impedances being proportioned in such manner that the input damping is approximately zero or negative.

An amplifier valve having a directly heated cathode naturally comprises already two cathode leads, namely, the two heating current leads. Thus, in principle, use may be made of the circuit shown in Fig. 1 of the accompanying drawing which is set out in greater detail hereinafter and in which the two heating-current supply conductors perform the functions of the above-mentioned cathode leads.

This circuit, however, has the disadvantage that the resistance of the filament brings about a supplementary damping of the input oscillatory circuit.

According to the invention this disadvantage is obviated by providing a cathode with at least three leads, two of which are connected to one of the ends of the cathode and are included, for the oscillations to be amplified, in the input circuit and in the output circuit respectively, whereas a third lead is connected to the other end of the cathode and only serves for the supply of heating current.

In order that the invention may be clearly understood and readily carried into effect it will now be described more fully with reference to the accompanying drawing, in which

Fig. 1 shows the circuit above referred to according to the prior application with the use of a directly heated tube, and

Figs. 2 and 3 show embodiments according to the present invention.

The circuit shown in Fig. 1 includes an amplifier valve comprising a directly heated cathode 2, provided with two leads, a control grid 3, a screening grid 4, a suppressor grid 5 and an anode 7. The high-frequency oscillations to be ampli-

fied are fed to an input oscillatory circuit 12 which is connected on the one hand to the control grid 3 and on the other hand, via one of the cathode leads, to the cathode 2. The anode 5 1 is connected to the cathode 2 via an output-oscillatory circuit 13, from which the amplified oscillations are taken off, and via the other cathode lead.

The cathode leads include inductances L₁ and L₂ and the point 8 of the inductance L₁ which point is adjacent to the cathode, is connected to the control grid 3 via a capacity C₁ and the end of the inductance L₂ (9) which is remote from the cathode is connected to the control grid via a capacity C₂.

The screening grid 4 is connected, via a capacity C₃, to that end of the inductance L₂ which is remote from the cathode so that the natural capacity between the control grid and the screening grid assists in the action of the capacity C₂. The suppressor grid 5 is also connected to the point 9.

The heating current which is received from a battery 17 is supplied to the cathode 2 via high-frequency choke coils 15 and 16 which prevent any short-circuit of the inductances L₁ and L₂ for the oscillations to be amplified. The other sources of supply are omitted for the sake of simplicity.

As set out in the prior application it can be ensured by correct proportioning of the elements L₁, L₂, C₁ and C₂ that the input damping which occurs due to the finite transit time of the electrons is suppressed so that the consequential input damping becomes zero or even negative. The elements L₁, L₂, C₁ and C₂ can be formed in part but not all of them by the natural inductances of the cathode leads and the natural tube capacities.

However, the circuit has the disadvantage that the resistance of the filament is connected in parallel with the input oscillatory circuit 12 via the capacity C₂ and the inductances L₁ and L₂ so that an undesired supplementary damping of the input oscillatory circuit is brought about.

According to the invention this disadvantage may be obviated by the use of a directly heated tube comprising three cathode leads as shown in Figs. 2 and 3.

In the circuit shown in Fig. 2 the left-hand end of the filament 2 has connected to it two leads which are included respectively in the input circuit and in the output circuit and in which inductances L₁ and L₂ are included. The right-hand end of the filament has connected

to it a third lead which solely serves for the supply of heating current and in which a high-frequency choke coil 18 is included. The lead included in the output circuit is used as a return-lead for the heating current and for this purpose the heating current supply battery is connected between the end of the choke coil 18 which is remote from the cathode and the point 9. As a rule, the heating current supply battery must be earthed so that in this case the output oscillatory circuit is also connected to earth in a high-frequency manner. In this case the circuit arrangement may be as shown in Fig. 2 in which the output oscillatory circuit and the end of the choke coil 18 which is remote from the cathode are jointly connected to earth, whilst the battery is short-circuited by a condenser 19 in a high-frequency manner. Instead thereof the point 9 could, of course, be connected to earth.

The choke coil 18 must be possessed of a considerable impedance for the oscillations to be amplified since the resistance of the filament 2 which is connected in parallel with the input oscillatory circuit via the capacity C_1 , the condenser 19, the choke coil 18 and the inductance L_1 may otherwise exercise a damping on that circuit.

In the circuit arrangement shown in Fig. 3 the lead included in the input circuit is used as a return lead for the heating current. For this purpose the battery 17 is connected between those ends of the choke coil 18 and the inductance L_1 which are remote from the cathode. If the battery is to be connected to earth the input oscillatory circuit is thus also connected to earth. The earth connection concerned may be provided, for example, as shown in the figure, at the end of the inductance L_1 which is remote from the cathode.

The circuit shown in Fig. 3 offers the advantage that the choke coil 18 may generally be possessed of a lower impedance than in the circuit shown in Fig. 2. On the other hand the connection of the input oscillatory circuit to earth entails some difficulty due to the capacity generally present between that end of the output oscillatory circuit 18 which is connected to the anode and earth, said capacity 20 being designated in Fig. 3 by dotted lines, since if the input oscillatory circuit is connected to earth a part of the anode current flows through the capacity 20 to earth and thence to the cathode through the inductance L_1 and this leads to a retroaction of the output energy on the input circuit and in addition brings about a supplementary damping of the input oscillatory circuit. If the input oscillatory circuit is earthed the anode lead and the output oscillatory circuit have therefore preferably to be screened capacitatively relatively to earth so that the capacity 20 is removed, it being necessary for the screening to be connected to point 9.

If the output oscillatory circuit is connected to earth, as is effected in the circuit arrangement shown in Fig. 2, a capacitative screening of the said kind is redundant.

What we claim is:

1. A circuit for the amplification of high frequencies, comprising an electron discharge tube provided with at least a directly heated filamentary cathode having two terminals, a signal in-

put grid and an anode, two leads connected to one cathode terminal and a third lead connected to the other cathode terminal, input and output circuits connected respectively to the input grid and to the anode, the grid return of the input circuit being connected to one of the first two cathode leads, the plate return of the output circuit being connected to the other of said two cathode leads, a condenser connected from each of the cathode leads to the signal input grid, a source of heating current having one terminal grounded connected between the third lead and one of the two other leads, and means for short-circuiting said heating current source with respect to high frequencies.

2. A circuit according to the invention defined in claim 1 wherein the grounded terminal of the heating source is connected to the third lead.

3. A circuit according to the invention defined in claim 1 wherein the grounded terminal of the heating source is connected to the cathode lead to which the input circuit grid return is connected.

4. A circuit according to the invention defined in claim 1 wherein an inductance is connected to each of the two first mentioned cathode leads, said inductances being included respectively in the input and output circuits, and a high frequency choke coil connected to the third cathode lead.

5. A circuit for the amplification of high frequencies, comprising an electron discharge tube provided with at least a directly heated filamentary cathode, a signal input grid, a screen grid and an anode, the cathode having two terminals with a pair of leads connected to one and a third lead connected to the other of said terminals, an impedance connected to each of said pair of cathode leads, input and output circuits connected respectively to the input grid and to the anode, the grid return of the input circuit being connected to the low potential end of the impedance connected to one of the pair of cathode leads, the plate return of the output circuit being connected to the low potential end of the impedance connected to the other of the pair of cathode leads, a condenser connected between the signal input grid and the cathode end of the impedance included in the input circuit, capacitive means connected between the signal input grid and the low potential end of the cathode impedance included in the output circuit, a high frequency choke coil connected to the third lead, a source of heating current having one terminal grounded connected between said choke coil and one of the cathode lead impedances, and means for short-circuiting said heating current source with respect to high frequencies.

6. A circuit according to the invention defined in claim 5 wherein the grounded terminal of the heating source is connected to the end of the high frequency choke coil remote from the cathode terminal.

7. A circuit according to the invention defined in claim 5 wherein the grounded terminal of the heating source is connected to the low potential end of the impedance which is included in the input circuit.
